US00D620928S

(12) **United States Design Patent**
Oliver

(10) **Patent No.:** **US D620,928 S**
(45) **Date of Patent:** **** Aug. 3, 2010**

(54) **RFID TAG ANTENNA**

(75) Inventor: **Ronald A. Oliver**, Seattle, WA (US)

(73) Assignee: **Impinj, Inc.**, Seattle, WA (US)

(**) Term: **14 Years**

(21) Appl. No.: **29/353,811**

(22) Filed: **Jan. 14, 2010**

Related U.S. Application Data

(62) Division of application No. 29/326,291, filed on Oct. 15, 2008, now Pat. No. Des. 611,037.

(51) **LOC (9) Cl.** **14-03**

(52) **U.S. Cl.** **D14/230**

(58) **Field of Classification Search** **D14/138,**

(57) **CLAIM**

The ornamental design for an RFID tag antenna, as shown and described.

DESCRIPTION

The FIGURE is a top plan view of an RFID tag antenna showing my new design.

The broken line showing of an RFID chip in FIGURE illustrates environment only and forms no part of the claimed design. The solid black areas constitute the entirety of the claimed design.
